CLAIM

The ornamental design for a weatherstrip for car door, as shown and described.

DESCRIPTION

FIG. 1 is a front, right side, top perspective view of a weatherstrip for car door showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the region denoted by the number "9" in FIG. 2.

The broken lines in the drawings show locations of break lines in FIGS. 1 through 8 and area of enlargement in FIGS. 2 and 9; the broken lines form no part of the claimed design. The claimed design is directed to the portions shown in FIGS. 1 through 9 and any portions not shown between the break lines form no part of the claimed design.
